CLAIM

The ornamental design for a footman loop, as shown and described.

DESCRIPTION

FIG. 1 is a right front perspective view of a footman loop showing our new design.

FIG. 2 is a front elevational view thereof.

FIG. 3 is a top plan view thereof.

FIG. 4 is a rear elevational view thereof.

FIG. 5 is a bottom plan view thereof; and,

FIG. 6 is a right side elevational view thereof, the left side elevational view being a mirror image of the right side elevational view.

In the drawings, the broken lines represent portions of the footman loop which form no part of the claimed design.
